UNITED STATES PATENT OFFICE.

HARRY L. JOHNSON, OF BATTLE CREEK, MICHIGAN, ASSIGNOR TO JOHNSON AUTOMATIC SEALER CO., LTD., OF BATTLE CREEK, MICHIGAN.

CARTON-SEALING MACHINE.

1,186,102.

Specification of Letters Patent.

Patented June 6, 1916.

Application filed October 5, 1914. Serial No. 865,083.

To all whom it may concern:

Be it known that I, HARRY L. JOHNSON, a citizen of the United States, residing at Battle Creek, Michigan, have invented certain new and useful Improvements in Carton-Sealing Machines, of which the following is a specification.

This invention relates to improvements in carton sealing machines.

10 My present improvements are especially designed by me for use on carton sealing machines such as are shown in U. S. Letters Patent No. 1,052,667, issued to me February 11, 1913, and I have illustrated my improvements herein as I have embodied the same in such a structure. My improvements are, however, desirable and capable of embodiment in other mechanisms of this class.

20 The main objects of this invention are to provide in a carton sealing machine an improved means for discharging or ejecting the sealed cartons from the forms and also to provide a mechanism which is simple and durable in structure.

25 Further objects, and objects relating to structural details, will definitely appear from the detailed description to follow.

I accomplish the objects of my invention by the devices and means described in the 30 following specification.

The invention is clearly defined and pointed out in the claims.

A structure which is a preferred embodiment of my invention is clearly illustrated 35 in the accompanying drawing forming a part of this specification, in which:

Figure I is a side view of a carton sealing machine embodying the features of my invention, certain details not particularly 40 relating to my present improvements being omitted. Fig. II is a detail vertical longitudinal section, the conveyer chain and carton holder being shown in full lines. Fig. III is a detail front perspective showing details of my improved ejector or 45 discharge mechanism. Fig. IV is a detail vertical section showing one of the ejectors and the operating connections therefor. Fig. V is an enlarged detail section on a line cor-

50 responding to line 5—5 of Fig. I.

In the drawing similar reference numerals refer to similar parts throughout the several views, and the sectional views are taken looking in the direction of the little 55 arrows at the ends of the section lines.

Referring to the drawing, the frame in the structure illustrated comprises suitable side members 1 connected by the bottom cross sills 2. The frame is suitably shaped to support the operating parts. At its rear end the frame has a superstructure 3 which supports parts of the flap folding and gluing mechanism. Disposed centrally and longitudinally of the frame is a conveyer or carrier way comprising a top member 4 and a bottom member 5, the top member being mounted above the frame cross pieces 6, while the bottom member 5 is mounted below it. At the front and rear ends of these carrier ways and disposed centrally between them are sprocket wheels 7 and 8 for the carrier or conveyer chain 9. The frame-like carton holders 10 are mounted at suitable intervals upon this chain 9. The sprocket 8 is mounted on the shaft 11 at the front end of the machine, while the sprocket 7 is mounted on the shaft 12 at the rear end of the machine. The shaft 12 is driven from the driving shaft 13, which is provided with a belt 14, through the sprocket chain 15, the sprockets for the chain 15 not being illustrated as they will be readily understood.

The cartons to be sealed are placed upon the holders 10 at the front end of the machine. The holders are provided with rests or stops 16 for the ends of the cartons.

As the cartons are carried along by the conveyer the inner flaps are folded by the mechanism, designated generally by the numeral 17, which is driven through the sprocket chain 18 from the shaft 12. As the details of the flap folding mechanism form no part of my present invention they are not further described herein, but they are preferably those illustrated and described in detail in my patent above referred to. After the inner flaps are folded glue is applied to the side flaps by a gluing mechanism, designated generally by the numeral 19. The gluing mechanism is connected to the driving shaft 13 by the gears 20. The details of this gluing mechanism are not illustrated or described but suitable mechanism is shown in my aforesaid patent. At the rear of the gluing mechanism is a curved flap retainer 21 which holds the inner flaps in their folded position as the cartons are carried by the holders over the rear conveyer sprocket to the side flap folding 110

mechanism below, designated generally by the numeral 22. The details of this mechanism are not shown as they form no part of my present invention and suitable mechanism is shown and described in my aforementioned patent.

As the sealed cartons pass from the sealing mechanism 22 they are engaged by the retaining rollers 23, which are connected by a train of gears so as to be driven in proper direction. These rollers are connected to the shaft 25 by the sprocket chain 26 and suitable sprocket wheels, not shown.

To discharge the sealed cartons from the forms I provide a pair of ejectors 27 which are mounted to reciprocate in the supports 28 so that the conveyer holders successively pass between them as they are carried along by the conveyer. These ejectors or push bars are provided with plate-like heads 29 having grooves 30 at their inner ends adapted to receive the edges of the cartons. The ejectors or push bars 27 are actuated by arms 31 on the rock shafts 32 disposed at the sides of the path of the conveyer forms. The supports 28 for the push bars or ejectors 27 are provided with bearings 33 on the shaft 11. This allows for the oscillating movements of the arms 31 which are pivotally connected at 34 to the push bars and also permits the oscillation of the ejectors so that they travel or swing with the carton holders on their work strokes as the holders pass over the conveyer sprocket wheel 8.

The holders swing between the ejectors while the ejectors are in their retracted position. The bases of the holders are somewhat narrower than their sides so that the heads 29 swing under the edges of the cartons. To allow the holders to swing from between the ejectors after the cartons are discharged the sides of the holders are notched at 10°.

The rock shafts 32 are provided with arms 35 which are connected by the links 36 to arms 37 on the actuating shaft 38. This actuating shaft is provided with an arm 39 connected by the link 40 to a lever 41 pivoted at 42 and actuated by the cam 43 on the conveyer driving shaft 12. This driving connection of the ejector mechanism to the conveyer shaft 12 insures proper timing of the ejector mechanism with the conveyer.

My improved ejector mechanism delivers or discharges the sealed cartons at the front of the machine and in a manner that does not distort or injure them.

I have illustrated and described my improvements in the form in which I have embodied the same in practice. I have not attempted to illustrate or describe various modifications or adaptations which I contemplate as I believe the disclosure made will enable those skilled in the art to which my invention relates to embody or adapt

the same as conditions may require. I desire, however, to be understood as claiming my improvements specifically in the form illustrated as well as broadly within the scope of the appended claims.

70

Having thus described my invention, what I claim as new and desire to secure by Letters Patent, is:

1. In a structure of the class described, the combination with a conveyer comprising driving and driven conveyer shafts, sprocket wheels on said shafts, and a conveyer chain provided with carton holders, of a pair of reciprocating ejector bars disposed one at each side of the conveyer so that the holders pass between them as the holders pass over said sprocket on said driven shaft, supports for said ejector bars having rocking bearings on said driven shaft, a pair of rock shafts disposed one at each side of the path of the conveyer holders, arms on said rock shafts pivotally connected to said ejector bars, an actuating shaft having arms thereon, arms on said rock shafts, links connecting said arms on said actuating shaft to said arms on said rock shafts, an actuating arm on said actuating shaft, a cam on said driving shaft, a lever actuated by said cam, and a link connecting said actuating arm on said actuating shaft to said lever.

75

2. In a structure of the class described, the combination with a conveyer comprising driving and driven conveyer shafts, sprocket wheels on said shafts, and a conveyer chain provided with carton holders, of a pair of reciprocating ejector bars disposed one at each side of the conveyer so that the holders pass between them as the holders pass over said sprocket on said driven shaft, supports for said ejector bars having rocking bearings on said driven shaft, a pair of rock shafts disposed one at each side of the path of the conveyer holders, arms on said rock shafts pivotally connected to said ejector bars, and driving connections from said rock shafts to said driving shaft.

80

3. In a structure of the class described, the combination of a conveyer chain provided with carton holders, a shaft, a conveyer sprocket on said shaft, reciprocating ejectors disposed so that the holders pass between them as the holders pass over said sprocket, supports for said ejector bars having rocking bearings on said shaft, rock shafts, arms on said rock shafts pivotally connected to said ejector bars, an actuating shaft having arms thereon, arms on said rock shafts, links connecting said arms on said actuating shaft to said arms on said rock shafts, and driving connections from said conveyer to said actuating shaft.

85

4. In a structure of the class described, the combination of a conveyer chain pro-

vided with carton holders, a shaft, a conveyer sprocket on said shaft, reciprocating ejectors disposed so that the holders pass between them as the holders pass over said 5 sprocket, supports for said ejector bars having rocking bearings on said shaft, rock shafts, arms on said rock shafts pivotally connected to said ejector bars, and means for actuating said rock shafts timed to 10 actuate said ejectors as the holders pass between them.

5. In a structure of the class described, the combination of a conveyer chain provided with carton holders, a shaft, a conveyer sprocket on said shaft, reciprocating ejectors disposed so that the holders pass between them as the holders pass over said 15 sprocket, supports for said ejectors having rocking bearings on said shaft, and means 20 for reciprocating said ejectors and rocking their said supports as the holders pass the same.

6. In a structure of the class described, the combination of a conveyer chain provided with carton holders, a shaft, a conveyer sprocket on said shaft, a reciprocating ejector, a support for said ejector having rocking bearing on said shaft, and means 25 for reciprocating said ejector and oscillating its said support.

7. In a structure of the class described, the combination of a conveyer chain provided with carton holders, a shaft, a conveyer sprocket on said shaft, a reciprocating 35 ejector, said ejector having a head with a groove therein adapted to engage the edges of the cartons, a support for said ejector having rocking bearing on said shaft, and means for reciprocating said ejector and oscillating its said support.

8. In a structure of the class described, the combination of a conveyer provided with carton holders, a wheel around which said conveyer travels, a reciprocating ejector, 45 a support therefor mounted for oscillation about the axis of said wheel, and means for actuating said ejector and oscillating its said support timed so that the ejector is actuated as the carton holders pass over said 50 wheel.

9. In a structure of the class described, the combination of a conveyer provided

with carton holders, a shaft, a conveyer sprocket on said shaft, a reciprocating ejector, a support for said ejector mounted 55 on said shaft, a rock shaft, an arm on said rock shaft pivotally connected to said ejector, and driving connections from said conveyer to said rock shaft.

10. In a structure of the class described, 60 the combination of a conveyer provided with carton holders, reciprocating ejectors disposed so that the carton holders pass between them, said ejectors having inwardly projecting heads, the sides of the holders being wider than their bases so that the inner 65 edges of the heads travel within the planes of the holder sides on their ejecting stroke, the sides of the holders being notched to permit the holders to swing from between 70 the ejectors while the ejectors are in their outer positions.

11. In a structure of the class described, the combination of a conveyer provided with carton holders, reciprocating ejectors disposed so that the carton holders pass between them, said ejectors having inwardly 75 projecting heads which travel within the planes of the holder sides on their ejecting stroke, the sides of the holders being notched 80 to permit the holders to swing from between the ejectors while the ejectors are in their outer positions.

12. In a structure of the class described, the combination of a conveyer chain provided with carton holders, a shaft, a conveyer sprocket on said shaft, an ejector arm support having rocking bearing on said shaft, a rock shaft, an ejector actuating arm on said rock shaft, an ejector pivotally connected to said arm and mounted on said support, and driving connections from said conveyer to said rock shaft whereby the ejector is actuated to eject cartons from the carton holders as the same pass over said 95 sprocket wheel.

In witness whereof, I have hereunto set my hand and seal in the presence of two witnesses.

HARRY L. JOHNSON. [L. s.]
